UNITED STATES PATENT OFFICE.

DAVID SCOTT ALLISON, OF SALT LAKE CITY, UTAH, ASSIGNOR TO SULLIVAN MACHINERY COMPANY, A CORPORATION OF MASSACHUSETTS.

MINING MACHINE.

Application filed January 23, 1918. Serial No. 218,280.

To all whom it may concern:

Be it known that I, DAVID SCOTT ALLISON, a citizen of the United States, residing at Salt Lake City, in the county of Salt Lake 5 and State of Utah, have invented certain new and useful Improvements in Mining Machines, of which the following is a full, clear, and exact specification.

My invention relates to mining machines. 10 It has for its object to provide an improved mechanism for cutting a kerf in the material to be mined in an improved manner whereby that material may be subsequently removed with greater facility. A 15 further object of my invention is to provide an improved mining machine adapted to cut a relatively wide kerf and thereby, when the coal is shot, cause the same to be rolled forward and broken up in such a 20 manner as greatly to facilitate the loading operation. These and other objects and advantages of my improved construction will, however, hereinafter more fully appear.

25 In the accompanying drawings I have shown for purposes of illustration one embodiment which my invention may assume in practice.

In these drawings,—

30 Fig. 1 is a side elevation, partially in section, of a mining machine equipped with my improvement.

Fig. 2 is a partial side elevation of the machine shown in Fig. 1, portions of the 35 same being broken away to illustrate the operating mechanism.

Fig. 3 is a detail view of one of the bearings for the supplemental cutting element.

Fig. 4 is a diagrammatic view showing my 40 improved machine ready to make its sumping or starting cut.

Fig. 5 is a similar view showing the machine after it has been sumped into the coal.

Fig. 6 is a similar view showing the machine at the end of its transverse cut.

50 In this illustrative construction, I have shown my invention applied to a self-propelled mining machine of a standard form which is herein shown to include a frame 1 mounted upon a suitable shoe 2 and provided with a forwardly extending cutter bar 3 equipped with the usual cutter chain 4. As usual in such machines, a motor 5 is carried by the frame 1, and connected 55 through suitable driving connections with

a cutter chain driving sprocket and any suitable feeding means adapted to use in propelling the machine during its different operations. In this illustrative construction, it will be noted that the motor 5 is connected through gears 6 and 7, a shaft 8, and gears 9 and 10, in such a manner as to drive a cutter chain driving sprocket 11, and that the gear 10 is also connected through usual friction controlled reduction 65 gearing (not shown) operatively connected between the upper end of the shaft 12 of the gear 10 and the upper end of a shaft 13 carrying a feed driving member 14, herein shown in the form of a sprocket, adapted to 70 act upon a flexible feeding member or chain 15. As usual, the operation of each of these elements 11 and 14 is also of course controlled by the usual controlling mechanism (not shown).

75 In my improvement, it will be observed that a supplemental cutting element 16 is provided, which is disposed above the cutter chain 4 and at an angle thereto, and preferably centrally of the cutter bar, in such a 80 manner as to cooperate therewith in cutting a relatively wide, and herein substantially V-shaped, kerf which opens out toward the face. In the form of my invention shown, this supplemental cutting element is 85 in the form of a rotating cutter bar, preferably tapered toward its front end, and having a plurality of cutter teeth 17 on its periphery, the same herein being shown as disposed in a plurality of parallel series, although obviously other arrangements of 90 these teeth may be utilized if desired. This bar, as shown, is also preferably disposed at such an angle relative to the cutter bar 3 as to bring its front end adjacent the bar at 95 a point intermediate the ends of the latter, and preferably slightly nearer the front end thereof. In a preferred form, the front end of this rotating bar also extends into a suitable centrally located aperture 18 in the bar 100 3 and is provided with a reduced portion 19 adapted to be received in a suitable bearing 20 located in said aperture. As shown, the upper end of the rotating bar is also preferably journaled in a suitable bearing 21 105 carried on the top of the frame 1 and at the front end thereof, the two bearings 20 and 21 thus cooperating to form a rigid construction. In a preferred form, the supplemental cutting element is also preferably con-

110

5 connected to a suitable source of power, preferably in such a manner as to enable it to be rotated whenever the cutter chain 4 is in operation. Obviously, any suitable source of power may be utilized. Herein, however, for simplicity, I have shown this supplemental cutting element to be driven from the motor 5, the same being provided for this purpose with a shaft 22 which extends rearwardly and upwardly from the bearing 21 and is journaled in a suitable support 23 carried on the upper surface of the frame 1. As shown, this shaft 22 is also connected through beveled gearing 24, housed in a suitable casing 25, with a removable extension 26 carried on the upper end of the shaft 8. Thus, it will be observed that as the shaft of the motor 5 is rotated to rotate the chain driving sprocket 11, the rotation thereof is transmitted through the shaft 8 to the gear 24 and the shaft 22 to the supplemental cutting element 16, in such a manner as to cause the latter to rotate simultaneously therewith.

20 In the operation of my improved construction, it will be evident that when the feeding element 15 is connected in a well known manner to the face, as, for instance, shown in Fig. 4, the machine may be sumped in under the coal as a unit in the usual manner 25 to cut a complete or full depth kerf in one operation, the supplemental cutting element 16 then rotating and cutting out its own path as the machine is moved bodily to the left from the position shown in Fig. 4 to 30 the position shown in Fig. 5. After this position has been reached and the flexible feeding element has been connected as shown in Fig. 6, in preparation for the transverse movement of the machine, the latter may 35 then also be operated as a unit in the usual manner to make its transverse cut. During this cut, however, it will be observed that as a result of the action of the supplemental cutting element 16 and its cooperation with 40 the cutter chain 4, a V-shaped kerf will be cut in the face. It will also be noted that the coal between these cutting elements 4 and 16 is broken up due to the simultaneous operation 45 of the two cutting elements on the opposite sides of the same. Obviously, when the machine reaches the opposite rib i. e. when the same completes its transverse cut, the machine may then be operated as is usual 50 in squaring up the rib.

55 As a result of my improvement, it will be observed that I am able to produce a relatively wide kerf of such a character that when the coal is shot from the top, as in the usual shooting operation, the same is caused 60 to be both rolled forward and broken up, in such a manner as greatly to facilitate loading, and especially machine loading. So far as the machine is concerned, it will also be noted that it is possible to apply my invention to an undercutting machine of standard

construction with only slight changes therein, and to remove the wide kerf cutting attachment whenever it is desired to undercut a kerf of standard dimensions, as by simply removing the bearings 21, 23, disconnecting 70 the supplemental shaft 26, and withdrawing the cutting element 16 from its socket 20. These and other advantages of my improved construction will, however, be clearly apparent to those skilled in the art. 75

80 While I have in this application specifically described one embodiment which my invention may assume in practice, it will be understood that this form of the same is used for purposes of illustration, and that the invention may be modified and embodied in other forms without departing from its spirit or the scope of the appended claims.

85 What I claim as new and desire to secure by Letters Patent is:

90 1. In a mining machine, a frame slidable on a mine bottom, means for sumping the same, and means comprising a plurality of cooperating relatively movable cutter carrying elements thereon for cutting in one sumping operation a full depth kerf having an inclined surface.

95 2. In a mining machine, a frame slidable on a mine bottom, and means comprising a plurality of cooperating relatively movable cutter carrying elements thereon for cutting out in a single transverse operation a substantially V-shaped full depth kerf disposed transversely of a face.

100 3. In a mining machine, a frame slidable on a mine bottom, a plurality of intersecting cutting elements thereon movable therewith and disposed in intersecting planes, and means for sumping said elements full length into the work in one operation.

105 4. In a mining machine, a frame slidable on a mine bottom, and relatively angularly disposed undercutting elements projecting forwardly therefrom and adapted to cut a full depth transverse kerf in one operation as said frame is moved transversely of a face.

110 5. In a mining machine, a frame slidable on a mine bottom, relatively inclined undercutting elements movable therewith and projecting forwardly therefrom and cooperating to form a single kerf, and feeding means operative to successively sump and transversely move said frame during cutting.

115 6. In a mining machine, a frame slidable on a mine bottom, and a plurality of undercutting elements thereon, one disposed at an angle relative to the horizontal and supported on the other side of said frame.

120 7. In a mining machine, a frame slidable on a mine bottom, a plurality of intersecting relatively inclined and relatively movable cutter carrying elements movable therewith, a motor on said frame, and means

- for simultaneously driving each of said cutter carrying elements therefrom.
8. In a mining machine, a frame, and means for cutting a single kerf including a plurality of relatively inclined undercutting elements on said frame, each carrying a plurality of cutters and one disposed in a plane intersecting the other at a point intermediate its ends. 70
9. In a mining machine, a frame, and means for cutting a single kerf including a plurality of relatively inclined undercutting elements on said frame, each carrying a plurality of cutters and one disposed in a plane intersecting the other at a point adjacent its front end but in rear thereof. 75
10. In a mining machine, a frame, cutting mechanism thereon including a cutter bar and cutter chain, a supplemental relatively inclined cutting element, and means for sumping said cutter elements full length into the face in one operation. 80
11. In a mining machine, a frame, a cutter bar and cutter chain thereon, a supplemental angularly disposed cutting element having its front end disposed adjacent the plane of said bar, and means for cutting a full depth transverse kerf with said elements during one transverse movement thereof. 85
12. In a mining machine, a frame, a cutter bar thereon, a cutter chain on said bar, and a rotating cutter bar carried on said frame and disposed in inclined position with respect to said first named bar. 90
13. In a mining machine, a frame, a cutter bar and cutter chain thereon, chain operating mechanism, a supplemental cutting element inclined relative to said bar, and operative connections between the same and said operating mechanism. 95
14. In a mining machine, a frame, a cutter bar and cutter chain thereon, a rotating cutter bar disposed above said first named bar and inclined relative thereto, and means for operating said cutter chain and said rotating bar. 100
15. In a mining machine, a frame, a cutter bar and cutter chain thereon, a rotating cutter bar disposed above said first named bar inclined relative thereto and having one end intersecting the plane of cut thereof, and means for simultaneously operating both said cutter chain and said rotating bar. 105
16. In a mining machine, a frame, kerf cutting mechanism thereon, a relatively inclined and cooperating kerf cutting element driven by said mechanism and cooperating with said cutting mechanism to form a single kerf, and means whereby said element may be applied to or removed from said frame at will. 110
17. In a mining machine, a frame, kerf undercutting mechanism thereon, operating mechanism therefor, feeding mechanism 115
- driven by said operating mechanism, and an inclined cooperating kerf cutting element likewise operatively connected to said operating mechanism and cooperating with said undercutting mechanism to cut a single kerf. 120
18. In a mining apparatus, a complete mining machine having a cutter bar and slidably on a mine bottom transversely of a face, and relatively movable means thereon cooperating with said bar to cut in one transverse movement of said machine relative to the face a single transverse kerf of full depth and having an inclined upper surface. 125
19. In a mining apparatus, a frame slideable on a mine bottom, means for sumping and moving the same transversely, and means on said frame comprising a plurality of elements carrying relatively movable cutters simultaneously operative during a single sumping movement of said frame and a single subsequent transverse movement thereof to insert a full depth undercut in a face and simultaneously slope toward the face the upper wall of the kerf adjacent the face. 130
20. In a mining machine, a frame slideable on a mine bottom, a plurality of relatively inclined cutting elements thereon, each carrying a plurality of cutters movable relative to the cutters on the other, a motor on said frame, means for simultaneously driving each of said cutting elements from said motor, and feeding means likewise driven by said motor for sumping said elements full depth into a face in one operation. 135
21. In a mining machine, a frame slideable on a mine bottom, a plurality of relatively angularly disposed cutting elements thereon, each carrying a plurality of cutters movable relative to the cutters on the other, a motor on said frame, means for simultaneously driving each of said cutting elements from said motor, and feeding means likewise driven by said motor for feeding said frame when said cutting elements are at full depth in a face, transversely of the face. 140
22. In a mining machine, a frame slideable on a mine bottom, a plurality of relatively angularly disposed cutting elements thereon, each carrying a plurality of cutters movable relative to the cutters on the other, a motor on said frame, means for simultaneously driving each of said cutting elements from said motor, and feeding means likewise driven by said motor for successively sumping said cutting elements full depth into a face and feeding said frame bodily transversely thereof. 145
23. In a mining machine, a complete mining machine slideable on a mine bottom and including a cutter bar, a cutter chain movable about the same, flexible feeding mechanism for successively sumping and feeding said machine relative to a face, and a mecha-

nism driven by said machine during successive sumping and transverse feeding operations for sloping toward the face the upper wall of a kerf cut by said machine.

- 5 24. In a mining machine, a complete mining machine slideable on a mine bottom and including a cutter bar, a cutter chain movable about the same, flexible feeding mechanism for successively sumping and feeding 10 said machine relative to a face, and mechanism driven by said machine during successive sumping and transverse feeding operations for sloping toward the face the upper wall of a kerf cut by said machine, said 15 mechanism being removable at will to permit said machine to operate in its usual manner.

25. A mining machine slideable relative to a mine bottom and having a cutter bar projecting therefrom, feeding means for feeding said bar into and transversely along a face to insert in one operation a full depth transverse kerf, and supplementary means driven by said machine and carried thereby 20 for in the same operation cutting away a portion of the face adjacent to and above the end of said bar adjacent the machine to form a surface facilitating the rolling out of the face after shooting.

- 30 26. In a mining machine, a frame slideable on a mine bottom, means for feeding said frame during sumping and cutting across a face, and cutting means on said frame operative during sumping to cut a triangular kerf in a vertical plane and during cutting across a face to cut intersecting plane kerfs forming a dihedral angle whose plane angle is equal to that angle of said triangular kerf which is opposite the working face.

40 27. In a mining machine, a frame slideable on a mine bottom during cutting, means for feeding said frame bodily over said bottom during sumping and cutting, and cutting means on said frame operative during sumping to cut a polygonal kerf and thereafter 45 on propulsion of said frame bodily across

the face during cutting to cut kerfs whose planes are parallel to certain of the sides of a similar polygon.

28. In a mining machine, a frame movable 50 rectilinearly in different directions during cutting, and cutting means thereon for cutting intersecting kerfs including cooperating elongated cutting elements each operative to cut with its major dimension disposed in a 55 plurality of substantially different relations to the direction of frame movement.

29. In a mining machine, a frame slideable on a mine bottom during cutting, means for feeding said frame bodily over said bottom 60 during sumping and cutting, and cutting means on said frame operative during sumping to cut a polygonal kerf and thereafter on propulsion of said frame bodily across the face during cutting to cut kerfs whose 65 planes are parallel to certain of the sides of a similar polygon, said cutting means including substantially horizontally disposed means for cutting one of said second mentioned kerfs, and means disposed at an angle 70 to said last mentioned means and intersecting the same at a point relatively remote from said frame for cutting another of said second mentioned kerfs.

30. In a mining machine, a frame slideable 75 on a mine bottom during cutting, means for feeding said frame bodily over said bottom during sumping and cutting, and cutting means on said frame operative during sumping to cut a polygonal kerf and thereafter 80 on propulsion of said frame bodily across the face during cutting to cut kerfs whose planes are parallel to certain of the sides of a similar polygon, said cutting means including a substantially horizontally disposed 85 cutter chain carrying cutter bar and a rotating cutter bar making an angle with the plane of said first mentioned cutter bar at a point remote from its rear end.

In testimony whereof I affix my signature.

DAVID SCOTT ALLISON.
